UNITED STATES PATENT OFFICE.

JOHN WILLIAM SCARTH, OF PUDSEY, AND WILLIAM ARTHUR THORNTON,
OF WETHERBY, ENGLAND.

APPARATUS FOR GENERATING ACETYLENE GAS.

SPECIFICATION forming part of Letters Patent No. 605,137, dated June 7, 1898.

Application filed October 25, 1897. Serial No. 656,339. (No model.)

To all whom it may concern:

Be it known that we, JOHN WILLIAM SCARTH, residing at Pudsey, and WILLIAM ARTHUR THORNTON, residing at Wetherby, in the county of York, England, subjects of the Queen of Great Britain, have invented new and useful Improvements in Apparatus for the Generation of Acetylene Gas and Like Purposes, of which the following is a specification.

This invention relates to improvements in means or apparatus employed for generating acetylene gas from calcium carbid or the like.

The objects of this invention are, first, to provide an apparatus for the production of acetylene gas from carbid of calcium and the like purposes and which automatically regulates in an extremely sensitive manner the generation to the consumption of gas, and, second, to provide suitable means for making up the charges of calcium carbid, which is or are placed in the generator in cartridge form, so as (a) to prevent the lime or carbid from blocking or stopping the water-supply pipe, (b) providing an easy, simple, cleanly, and quick means for recharging the generator, especially in the case of table-lamps, thereby preventing waste of carbid and any unpleasant odor arising from the pieces of carbid being left about the table or floor or other place and becoming damp, and (c) the safety of the charges is insured by inclosing them in water-proof tins or casings, which prevents any danger of explosion from the carbid becoming damp and generating gas, only one charge being taken out of its inclosing case at the same time and then only immediately before being placed in the generator. We attain these objects by mechanism illustrated in the accompanying drawings, in which—

Figure 1 is a vertical section of the entire apparatus; Fig. 2, an elevation drawn at a right angle to Fig. 1; Fig. 3, an elevation of a carbid holder and cartridge; Fig. 4, a vertical section of carbid-cartridge; Fig. 5, a reduced part plan of water-cylinder with a generator arranged within an external recess.

Similar letters refer to similar parts throughout the several views.

A is the gas-holder, which is closed at the side and top, but is open at the bottom. The

gas-holder A is inclosed within a longer water-cylinder B, with or without a top or removable cover B'. The gas-holder and water-cylinder may be made of any suitable material, such as metal, and of any convenient shape, such as round, square, hexagonal, or other contour. In the top of the gas-holder is provided a recess, hereinafter termed the "hollow cap C," which extends to a height, say, for example, slightly above the level of the water (shown at Fig. 1 by dotted line D) in the water-cylinder.

E is the generator, which is arranged at any suitable distance from and on the outside of the water-cylinder. The generator is preferably arranged close to the water-cylinder, or it may be arranged within a recess B², as shown at Fig. 5.

The generator E consists of a cylinder or other shaped vessel closed at the bottom and provided with a removable lid or cover E', which is secured in position by a hand-screw F, passing through a nut formed in a bridge G, capable of being moved in and out of position as circumstances require. The generator E is preferably water-jacketed at H, and the upper and lower ends of the water-jacket are placed in communication with the water-cylinder by means of the short pipes or tubes h h'.

The generator E contains the carbid-holder I, which is made to fit or pass within the generator.

The carbid-holder I may consist of a cylinder or other vessel, say, of wire, or preferably perforated sheet metal, or it may be made in skeleton form, as shown at Fig. 3, consisting of any desired number of uprights bound together by any desired number of transverse rings or stays i. This latter form of carbid-holder is applicable for use with the carbid-cartridge to be hereinafter described.

From the lower end of the generator, below the carbid-holder, a pipe, hereinafter called the "water-pipe J," passes through the bottom of the water-cylinder into the gas-holder and is carried up to within a suitable distance of its top, but below the water-level D, when the gas-holder is in its normal position. The pipe J is provided, say near the generator E, with a stop-cock or valve J' for cutting

- off the water-supply from the cylinder to the generator. A second pipe, hereinafter called the "gas-pipe K," passes from the upper end of the generator E, as presently described, to the upper part of the before-mentioned hollow cap C. The gas-pipe K immediately on passing from the generator E is first led upward for a short distance above the level of the water-line D in the water-cylinder, and it may be provided in either the ascending or descending branch thereof with a stop-cock L of any ordinary and suitable construction, (shown at Fig. 1 on the ascending branch,) or in place of the stop-cock, or in addition thereto, the descending branch of the gas-pipe K may be made in two separate portions k k', as shown at Fig. 1, the lower end of the portion k dipping below the level of the water in a small closed cylindrical or other shaped vessel, hereinafter referred to and termed the "water-lock M." The upper end of the lower portion k' of the gas-pipe K is arranged to terminate in and near to the top of the said closed vessel forming the water-lock M.
- Provision is made in the top of the water-lock M for the admission of water to its interior. The water forming the water-lock is arranged to cover the end of pipe k, say, about two inches, more or less, according to the size of the vessel M. When the lid E is removed, the pressure of the gas in the holder A forces the water in the closed vessel M up the pipe k, and by reason of the latter being smaller in diameter or of smaller area than the closed vessel M the pressure of the column of water in the pipe k is increased, and thereby forms a complete and certain seal for preventing the gas escaping from the holder A and returning to the generator E.
- To prevent the condensation of the gas or water carried by the gas forming a water-lock in the horizontal portion of the pipe K, it may be provided with a siphon-tap of ordinary construction, or a branch pipe K^X, armed with a stop-cock, may be provided for connecting this portion of the pipe K with the collector-box O. By this means the water may be readily removed from the horizontal portion of the pipe K.
- From near the top of the interior of the before-mentioned hollow cap C a second pipe, preferably formed as a coil and hereinafter referred to as the "condenser-pipe N," passes down through the water in the gas-holder A to the upper part of a closed vessel O of any suitable size and shape conveniently attached, say, to the under side of the bottom of the water-cylinder B and hereinafter called the "collector-box." The gas-supply pipe P to the burners is taken from the upper part of the collector-box O and may be armed with a valve or stop-cock Q of any ordinary and suitable construction.
- The upper part of the gas-holder is formed with false conical or tapering sides or is lined with a wood or other packing to form a displacer R. When a circular gas-holder is em-

ployed, the displacer may be made in one piece, and the orifice at the top would be smaller than it is at the bottom. In cross-section its sides would then be cuneiform, and they are arranged with their largest portions against the top of the gas-holder, as shown at Fig. 1. As the gas-holder and displacer rise in the water-cylinder there will be an upward gradually-increasing size of the space for the gas within the gas-holder. Consequently the displacement of the water by the downward movement of the gas-holder increases at a much greater ratio than the increase of depth or movement of the gas-holder.

A funnel-shaped water-supply inlet S at the side of the water-cylinder and an opening or hole s are provided in the side of the water-cylinder for communication therewith.

T is an overflow-pipe attached to the funnel S.

A discharge-cock U is fitted to the bottom of the generator.

The case or cover or bag, all of which are hereinafter termed and included in the term "case V," in which the carbide-cartridge or charge, which is hereinafter termed the "charge," is placed, may be made of any suitable woven or manufactured fabric or material—such as, for example, say, of muslin of any desired mesh and strength—or of any suitable porous material—as, say, blotting-paper—or of any suitable perforated material—as, say, cardboard or the like, but preferably of muslin or cardboard. The case may be made to suit or conform to the inner shape or contour of the inner perforated or other holder of the generator, and it may, if desired, be provided and strengthened at the sides and bottom with one or more strands or thicknesses or pieces W of cloth, tape, wire, or equivalent material. To the top of the case may be attached by any suitable means a ring, hoop, loop, or its equivalent, all of which are hereinafter included in the term "loop Y," made of any suitable material—such as, say, metal, tape, or the like—for enabling the charge to be inserted in or withdrawn from the holder I of the generator E. A simple way of strengthening the sides and bottom, so as to prevent the charge forcing its way through the case V, falling into the lower part of the generator E, and stopping up the water-pipe J, is to secure, by sewing or otherwise, one or more strips of tape to the sides of the case V and under its bottom, as shown at Fig. 4, with or without an additional thickness of, say, cloth at the bottom of the case, and to unite the ends of the tape W at the top to form the loop Y; or, if so desired, the wire strands I and rings i may be incorporated in or secured to the case V. The casing may also be provided with draw-strings Z for closing its aperture or mouth, as shown by dotted lines at Fig. 3. When placing the calcium carbide (which is broken or powdered in or to any suitable size) within the case, care should be taken to

avoid quite filling it, (say from one-half to three-fourths full will be found sufficient,) so as to provide room for the expansion of the calcium carbid during the generation of gas.

5 These charges, formed into cartridges as herein described, may be either placed severally in a suitable water-tight tin or other casing, or they are each separately placed in one tin or casing, or they may, if desired, be covered 10 with thin sheet india-rubber or any other suitable waterproof material and securely folded and sealed in any suitable manner. This latter method is only preferable when more than one charge is contained in one tin 15 or case or when the tin is dispensed with.

The action of the apparatus is as follows: The charge contained in the case V is placed in the holder I of the generator E and its lid E' secured in position by the hand-screw F 20 after the bridge G has been turned into position. The water-cylinder B is filled through funnel S and opening s with water up to the water-level D, and the level of the water in the gas-holder then reaches close to the top 25 of the water-pipe J. On opening the supply-pipe P to the burners (not shown in the drawings) the gas previously generated and stored in the upper part of the gas-holder A passes down through the condenser-pipe N, thereby 30 allowing the gas-holder A to descend. In doing so the displacer R causes the water to rise in the gas-holder and overflow down the water-pipe J to the lower part of the generator E, and on coming in contact with the charge of 35 calcium carbid therein the water is decomposed and acetylene gas (C_2H_2) generated. The gas generated passes off from the upper end of the generator through the gas-pipe K to the hollow cap C in the upper part of the 40 gas-holder, and if the production is more rapid than the consumption the holder is raised and the water-level falls below the mouth of the water-pipe, stopping the water-supply and the generation of gas. The generation 45 of gas, however, does not cease immediately if there is a considerable quantity of water in the pipe, and this suffices to reach the level of the undecomposed carbid. By closing the before-mentioned stop-cock L or 50 by the automatic closing of the water-lock M, which is effected by the pressure of the gas from the holder A forcing a portion of the water in the closed vessel M up the pipe k, as previously described, the gas generated 55 may be prevented from passing direct to the gas-holder and exercising a back pressure on the water in the generator it forces the water back below the undecomposed carbid into the water-pipe. The cock L or the water-lock 60 M also serves the purpose of preventing a back flow of gas from the holder to the generator, which provision is necessary to prevent the gas escaping back from the gas-holder when the generator is being recharged.

65 By the use of the herein-described apparatus the following advantages are secured in

addition to there being less heat than when coal-gas is used, namely:

First. There is an automatic supply of water to generator, insuring constant and regular supply of gas. 70

Second. The vapor is entirely condensed before entering the main service-pipe.

Third. The pressure of gas remains always the same under every circumstance, and that 75 without the addition of any costly and always unsatisfactory regulator.

Fourth. The total exclusion of air, and therefore uniform and steady light.

Fifth. The apparatus can be recharged with 80 absolute safety without any alteration of apparatus, and that when the gas is burning.

Having now particularly described and ascertained the nature of the said invention, what we claim, and desire to secure by Letters Patent, is—

In apparatus for generating acetylene gas from calcium carbid, the combination of the gas-holder A inclosed within a water-cylinder B partially filled with water and provided with 90 an inlet-funnel S and overflow-pipe T, a gas-chamber C in top of the said gas-holder, a conical displacer R arranged within the said gas-holder near its top, a gas-generating chamber E arranged at the side of the said water-cylinder, closed at its top by lid E' and provided with a water-jacket H in communication at its top and bottom by means of pipes h h' with the said water-cylinder, bridge G and screw F for retaining the lid E' in position, perforated carbid-holder I inserted within the generator E, a cartridge-case V constructed as described, and provided at its base and sides with strengthening-pieces W and at its top with a loop Y, for receiving 105 the charge of calcium carbid, water-pipe J communicating respectively with the bottom of generator E, and interior of the gas-holder A, and armed with a stop-cock J', gas-pipe K divided into two portions, one of which is 110 armed with a stop-cock L, said gas-pipe being in communication at its extreme ends respectively with the gas-chamber C and top of the generating-chamber I, a water-lock M interposed between the extremities of the said 115 gas-pipe for receiving the divided ends, a gas-cooling coil N in communication with the gas-chamber C and a collecting-box, a collecting-box O arranged at the base of the water-cylinder, a service-pipe P armed with a stop-cock 120 Q in communication with said collecting-box, and a discharge-cock U arranged at the bottom of the generator, all arranged and operating as set forth.

In testimony whereof we have hereunto 125 signed our names to this specification in presence of two subscribing witnesses.

JOHN WILLIAM SCARTH.

WILLIAM ARTHUR THORNTON.
